DANIEL M. SOMERS, OF NEW YORK, N. Y.

Letters Patent No. 82,650, dated September 29, 1868.

IMPROVED TUMBLER-WASHER.

The Schedule referred to in these Letters Patent and making part of the same.

TO ALL WHOM IT MAY CONCERN:

Be it known that I, DANIEL M. SOMERS, of the city, county, and State of New York, have invented a new and useful Improvement in Tumbler-Washers, of which the following is a full, clear, and exact description, reference being had to the accompanying drawing, forming part of this specification, and which represents a sectional elevation of my improved tumbler-washer.

My improvement in tumbler-washers consists in a tumbler-holder or inside-washer, of peculiar construction, being made with ribs or pendent arms, forming a frame, so shaped and constituted as to give it an elastic character, and wedge-presentation to the tumbler, for operation in connection with an automatic valve, and so that, in seating the tumbler on said frame, it is readily fitted thereon, or to its place of rest, without danger of breakage, and free from all liability of afterwards tipping off the same during such single adjustment of it, acting both by side pressure and weight on the frame, and serving, at the same time, to quickly open the valve, to admit a stream or streams of water, for play on or against the inside of the tumbler; in the arrangement of a turbine within the supply-stem, and relatively to the discharge-orifices of the outside-washer, to give a rotary motion to the latter, so that the water therefrom may be uniformly directed upon the tumblers, regardless of the variable force thereof. Said invention also covers a bouquet-vase, or its equivalent, at top of the central stem, constructed to form a valve for control of the water to the outside sprinkler, and made to rotate by means of a turbine arranged within the stem.

Referring to the accompanying drawing, A represents the counter on which the machine stands, and B the basin of the apparatus. Arranged within the latter is a central upwardly-projecting stem, C, here shown as made up of a base-portion, *a*, cylinder or box, *b*, and upper portion, *c*, formed of or with a vase or flower-holder, *d*, and outside-tumbler sprinkler or washer, *e*, said upper portion, with its vase and sprinkler, being made to revolve, on opening escape-apertures *f*, in the cylinder, by the action of a turbine, *g*, arranged within said cylinder, and made fast to a hollow supply-shaft or revolving pipe, *h*, that carries the sprinkler and vase, the latter, or its stem, being made to form a valve, *i*, on top of the shaft, for, by screwing down or partly unscrewing the vase or stem, shutting off, or opening, or regulating the supply of water to the sprinkler, and, when said valve is closed, without, if desired, (by reason of the continuous open connection of the turbine with the shaft *h*,) stopping the rotation of the bouquet-vase, that thus forms both an ornament and valve to the sprinkler. The base-portion, *a*, of the central stem C, has any suitable number of channels, *k*, or the basin may be equivalently grooved or constructed, to carry off the waste or soiled water from the basin into a common discharge-passage or main outlet-pipe, *D*, which, by the arrangement of the inlet-pipe or passage *E*, for water, under pressure within said common outlet, is the only part of the structure that requires a hole to be made in the counter, so that when the apparatus is removed, there is but one hole to plug. This reduces disfigurement of the counter, as compared with other arrangements involving separate openings, that is, one for the inlet and the other for the outlet.

The inlet-pipe *E*, which derives its supply, say, by a branch, *l*, below the counter, is in open communication with the hollow shaft *h*; also, by branch or lateral openings, with pipes *m*, above the counter, for conveying water to the tumbler-holders or inside-washers, which are arranged within the basin, around the central stem C, so that the same sprinkler, *e*, that, in revolving, has a centrifugal action, to effect a more perfect washing of the outside of the tumblers, acts in a uniform manner over a series of holders or tumblers lying thereon.

These tumbler-holders or inside-washers it is preferred to construct as follows: *F* is a stem, screwing on to the top of the bent extremity of the pipe *m*, and made with a vertical passage, *n*, up through it, in communication with the pipe *m*. On and around this stem are attached, at its top, so as to give them a pendent character, any desired number, but preferably three, ribs, *G G'*. One, *G'*, of these ribs is jointed, as at *o*, to the stem *F*, while the others may be permanently attached thereto at their upper ends, but all, by reason of their construction or mode of suspension, are more or less of an elastic character, so as to form a spring-frame, as it were, and so shaped or hung as to present a wedge-configuration or conical formation to the whole, which, in connection

with the elastic character of the ribs, facilitates the seating of the tumbler over the frame, and prevents breakage of the glass; also, restrains the tumbler from tipping off its holder, the tumbler, in being adjusted to its seat, acting both by weight and side pressure on the ribs. The jointed rib G', under this action of the tumbler, and while the latter is being let down to its seat, operates, as it is forced inwards, to quickly open the valve H, to admit water for washing the inside of the tumbler, a spring, r, serving to close said valve, and to throw the jointed rib G' outwards, when or as the tumbler is being removed from its holder, the spring, r, also answering to give increased elasticity to said rib.

What is here claimed, and desired to be secured by Letters Patent, is—

1. A tumbler-holder, consisting of a tubular stem, F, with fixed pendent arms, G, and a jointed arm, G', connected with and operating the valve H, in an automatic manner, substantially as described.
2. The arrangement of a turbine within the supply-stem, and relatively to the discharge-orifices of the outside-washer, to give a rotary motion to the latter, substantially as shown and described, for the purpose set forth.
3. The combination of the vase d, forming a valve, i, with a rotary tumbler-sprinkler, substantially as set forth.

D. M. SOMERS.
